UNITED STATES PATENT OFFICE.

EPIFANIO V. N. TOMASULO, OF CINCINNATI, OHIO.

DESIGN FOR A CASE FOR HAIR-CUTTING MACHINES.

59,440.

Specification for Design.

Patented Oct. 18, 1921.

Application filed April 4, 1921. Serial No. 458,548. Term of patent 14 years.

To all whom it may concern:

Be it known that I, EPIFANIO V. N. TOMASULO, a subject of the King of Italy, residing at Cincinnati, in the county of Hamilton and State of Ohio, have invented a new, original, and ornamental Design for Cases for Hair-Cutting Machines, of which the following is a specification, reference being had to the accompanying drawings, forming part thereof.

In the drawings:

Figure 1 is a plan view,
Fig. 2 is a bottom view,

Fig. 3 is a view of one side,
Fig. 4 is a view of the other side,
Fig. 5 is a view looking at the front or blade end and one side, and
Fig. 6 is a rear end view.

I claim:

The ornamental design for a case for hair cutting machines, substantially as shown.

EPIFANIO V. N. TOMASULO.
